(57) **CLAIM**

The ornamental design for a food holding implement, as shown and described.

DESCRIPTION

FIG. 1 is a front elevational view of a food holding implement showing my new design;

FIG. 2 is a side elevational view thereof;

FIG. 3 is a perspective view showing a cookie attached to a bottom end of the present invention; and,

FIG. 4 is a perspective view showing the present invention positioned with a beverage container with the cookie dunker into the beverage.

The broken lines are for illustrative purposes only and form no part of the claimed design.
